DUAL RESONANT JET PROPULSION ENGINE
FOR AIRCRAFTPaul H. Kemmer, Fairfield, and Herbert M.
Heuver and Frank L. Wattendorf, Dayton, Ohio

Application November 9, 1945, Serial No. 627,771

8 Claims. (Cl. 60—35.6)

(Granted under the act of March 3, 1883, as
amended April 30, 1928; 370 O. G. 757)

1

The invention described herein may be manufactured and used by or for the Government for governmental purposes without the payment to us of any royalty thereon.

This invention relates to jet propulsion motors and more particularly to dual jet propulsion engines for aircraft, having for one of its objects the provision of two or more jet propulsion units of the intermittent or resonant type having side-by-side, parallel jet reaction tubes connected together to discharge alternately from one tube to the other in synchronized relation, utilizing a portion of the discharge impulses from each combustion chamber and reaction tube to compress and fire the explosive mixture in the other combustion chamber.

A further object of the invention is the provision of a plurality of jet reaction tubes for a jet propulsion engine, shaped to form acoustical resonant spaces connected together to form shock wave conducting means within the spaces, causing cyclic pressure impulses of suction, compression, combustion and exhaust to occur alternately in the spaces, effecting a continuous and uniform thrust from the engine.

A further object is the provision of a plurality of resonant jet propulsion units constituting a jet propulsion engine in which the resonant cycle of fuel charging, compression, combustion and discharge of each unit is controlled by the cyclic operation of one of the other units to provide a substantially uniform thrust jet propulsion engine.

A still further object is the provision of a plurality of jet propulsion units constituting a jet propulsion engine utilizing the shock wave from each of the jet units, following the cyclic combustion in that unit, for compressing and firing the combustible mixture in another of the jet units.

A still further object is the provision of a dual jet propulsion unit having improved fuel supplying and pumping means for alternately supplying fuel to the jet units, in which the combustion pressure and shock wave in each of the units during the combustion therein constitutes pressure means for actuating the fuel supplying and pumping means to supply fuel to the other jet propulsion unit of the engine.

A still further object is the provision of a dual jet propulsion unit having pressure operated means adapted to be actuated by air pressure, due to the velocity of the air passing the unit, for varying the rate of fuel being supplied to the propulsion units.

2

Another object is the utilization of pressure operated means for varying the operation of the fuel supply means for a plurality of jet propulsion units, constituting a jet propulsion engine, in proportion to variations in the atmospheric pressure of the air surrounding the units.

A further object is the provision of a plurality of jet propulsion units constituting a jet propulsion engine, having means for causing the jet propulsion units to operate alternately, or continuously, and pressure operated means operable by the velocity of air passing the engine for changing the operation of the jet propulsion devices from an alternate operation to a continuous operation.

A further object is the provision of a jet propulsion engine having a jet propulsion unit with an athodyd form of surrounding casing, constituting supplemental propulsion means for the engine, utilizing the heat from the main reaction propulsion unit to supply heat to the air passing through the athodyd casing to effect the air expansion within the athodyd and the high velocity air discharge from the athodyd, supplying supplemental thrust to the engine.

Like reference characters refer to like parts in the several figures of the drawings in which:

Fig. 1 is a somewhat diagrammatic horizontal longitudinal sectional view through our improved dual jet propulsion engine.

Fig. 2 is a vertical sectional view taken approximately on the plane indicated by the line 2—2 of Fig. 1.

Fig. 3 is an end view of the front end of the engine illustrated in Figs. 1 and 2, somewhat diagrammatically illustrating the arrangement of the air admission tubes and the intermediate fuel spray jets.

Fig. 4 is a cross-sectional view taken through one of the dual jet propulsion units, on the plane indicated by line 4—4 of Fig. 2, illustrating the athodyd casing and the cooling fins between the same and the reaction jet tubes.

Fig. 5 is an enlarged detail sectional view through one of the valved air admission tubes.

Fig. 6 is an enlarged vertical cross-sectional view taken through one form of our improved fuel supply control means, illustrating the heads of the jet reaction tubes, and in full lines, the fuel delivery conduits and headers and spray nozzles for supplying fuel under pressure to the combustion chambers.

Fig. 7 is an enlarged detail view in elevation, similar to Fig. 6, illustrating a modified form of fuel delivery control unit or pump means.

Fig. 8 is a horizontal longitudinal sectional view illustrating a modified form of dual jet propulsion engine.

Fig. 9 is a front elevation of the modified form of dual jet engine illustrated in Fig. 8.

Referring more particularly to Figs. 1, 2 and 3 of the drawings, our improved jet propulsion engine includes a pair of side-by-side jet propulsion units or tubes as indicated at 1 and 2, disposed in parallel relation to each other. The propulsion units comprise enlarged spherical head members or combustion chambers 3 and 4, having reduced streamlined rearwardly extending discharge ports connected to rearwardly and outwardly diverging jet discharge tubes 5 and 6, terminating in discharge ports or openings 7 and 8.

A conduit 9, of a substantial diameter, approximately equal to the diameter of the forward end of the jet discharge tube 5 or 6, connects these two jet discharge tubes together. The conduit 9 is preferably U-shaped and is curved uniformly throughout its length with both of its ends facing forwardly in free communication with the interior of the reaction or jet discharge tubes 1 and 2, so as to alternately receive a portion of the jet discharge and the shock wave created thereby, from each jet tube and discharge the same into the other jet tube, conducting the jet gases and shock waves through the conduit and discharging the same in a forward direction, into the other jet discharge tubes at the other end of the conduit, for purposes later to be described.

Surrounding the primary jet discharge tubes 5 and 6, and a portion of the spherical combustion chambers 3 and 4, are a pair of communicating athodyd chambers or secondary thermal air jet thrust units 10 and 11, having annular air intake ports 12 and 13 at their forward ends with intermediate enlarged air heating chambers 14 and 15 extending rearwardly into the tubular thermal air discharge passages 17 and 18 which terminate in ring-like thermal air discharge ports 19 and 20.

Radial heat exchange fins 21 are carried by the spherical heads 3 and 4 and jet discharge tubes 5 and 6 between the same and the inner walls of the athodyd casing for cooling the combustion chambers 3 and 4 and the primary jet discharge tubes 5 and 6, upon the passage of air through the athodyd chamber to prevent them from reaching critical disintegrating temperatures. An exchange of heat from the throat or front end of the tubes 5 and 6 also takes place, heating and expanding the air passing therethrough, particularly in the enlarged portions of the athodyd chambers 14 and 15. A tubular connecting shell 22 surrounds the U-shaped passage 9, connecting the two athodyd chambers together, as best seen in Fig. 1.

Air is introduced into the spherical combustion chambers 3 and 4 in any well-known manner, such as by leaf spring valve means commonly employed in reaction jet propulsion devices of this type employing a reaction jet pipe, wherein the inertia of the gases passing from the combustion chambers rearwardly at high velocity in the jet discharge pipe, following the combustion in the spherical combustion chambers, creates a partial vacuum in the combustion chambers causing fresh air to be drawn through the air vents in the forward or head portions of the combustion chambers through the leaf spring reeds or check valves.

For purposes of illustration, the forward areas of each of the spherical combustion chambers 3

and 4 are provided with a plurality of closely and uniformly spaced air admission tubes 23, as best seen in Figs. 1, 3 and 5. These tubular members 23 extend forwardly from the combustion heads 3 and 4 in parallel relation to each other substantially in the direction of movement of the aircraft or other mobile unit carrying the dual jet engine.

These tubular air admission check valve members 23 are secured in suitable openings in the front portion of the spherical heads 3 and 4, each comprising a cylindrical tube 24 having a pair of thin flat spring valve members or reeds 25, 26 with their forward end portions 25' and 26' extending longitudinally across the inside of the tubular members, the rear portions 25'' and 26'' being curved and tensioned outwardly to engage the inner circular portions of the tubular members. Air circulation ports 27 are formed in the tubular members 23 adjacent the combustion heads 3 and 4 in opposed relation to each other in a plane at right angles to the plane of the forward portions 25', 26' of the reed members 25 and 26. The free ends and edges of the reed members 25, 26 are formed to fit the inner surface of the tubular members and are sufficiently flexible to yield toward each other when a predetermined reduction in the pressure within the combustion chambers occurs, and by the ram pressure of air entering the forward ends of the tubes. The combustion pressures of the fuel being burned within the spherical combustion chambers 3 and 4 forces the reeds closed to prevent gases from escaping forwardly past the tubular reed members 25 and 26.

Air is circulated through the air intake tubes 23 by the "ram effect," when the jet engine moves forward through the air, this air passing along the opposite sides of the reeds, and out through the openings 27, produces air circulation and cooling effect on the reed members and the tubular air intake members 23.

Referring more particularly to Figs. 1 and 3, fuel is sprayed into the spherical combustion heads, between the air intake tubes 23, at a plurality of uniformly spaced points, as illustrated in the drawings, under the control of a fuel delivery control unit, later to be described, and indicated diagrammatically at 28 in Figs. 1 and 3.

The fuel injection nozzles 29 extend into the combustion chambers 3 and 4 and are connected to fuel delivery headers 31 (Fig. 6) and supply pipes 30 which extend across the front portions of the spherical combustion heads 3 and 4 in parallel relation to each other, each pipe 30 having spray nozzles 29 connected thereto. A common header 31 may be employed for each combustion chamber for supplying fuel to the supply pipes 30.

Conventional spark plug means 32 is disposed in at least one of the spherical combustion chambers, as indicated in Fig. 1, including suitable conventional operating means, not shown, for energizing the plug to fire the mixture in the combustible chamber 3, and start the dual jet engine into operation.

Referring now to Fig. 6, our improved fuel supply control unit as diagrammatically illustrated at 28 in Fig. 1 will now be described. The fuel supply control unit 28 is suitably carried by the jet engine, preferably between the heads 3 and 4 and the jet tubes 5 and 6, and comprises a valve casing 33 having two valve chambers 33a and 33b, connected by fuel conducting passages 35 and 36, to the headers 31. A fuel chamber 37 is provided, having a fuel inlet passage 38, with

a needle valve 39 therein, the passage 38 being connected at its other end to a fuel reservoir 40.

The valve chambers 33a and 33b are formed with valve seats 41 and 42 therein, receiving poppet valves 43 and 44 having stems 45 and 46 extending through the casing to the exterior thereof with the ends of the valve stems connected respectively to a pair of centrally pivoted levers 47 and 48, pivoted at 49 on a rigid bracket 50 depending from the valve casing 33. The longer arms 47' and 48' of the levers 47 and 48 are connected by actuating rods 52 and 53 to pressure operated bellows members 54 and 55, preferably of the "Sylphon" type. These bellows members 54 and 55 are expanded by pressure supplied through conduits 56 and 57 from the spherical combustion chambers 3 and 4. When an explosion occurs in one of the combustion chambers, such as the chamber 4, the pressure therein becomes effective through the conduit 57, on the bellows 55 to rock the lever 47 clockwise to unseat the valve 43, permitting fuel from the tank 40 to flow through passage 38, chamber 37 and passage 35 into the headers 31 and through the supplemental supply pipes 30, and spray nozzles 29, into the other combustion chamber 3, supplying the latter combustion chamber with fuel incident to pressure resulting from the explosion in the combustion chamber 4. Springs 58 and 59 normally close the valves 43 and 44 except when actuated by the bellows members 55 and 56, and maintain the bellows members in their collapsed conditions.

The longer lever arms 47' and 48' of the levers 47 and 48 have spring seats 60 and 61 projecting therefrom, between which is interposed a fairly stiff return spring 62 designed to be tensioned by movement of one of the levers 47 or 48 to rock the other lever 48 or 47 to move the opposite valve to its closed position as the other lever moves its valve to open position.

The needle valve 39, which controls the rate of fuel flow through the passage 38 between the fuel tank 40 and the fuel chamber 37 is adjustable for a predetermined ratio between the altitude and speed of travel of the craft carrying the dual jet engine, since the proper explosive mixture of fuel and air introduced into the combustion chamber depends on the air speed or ram effect of air entering the combustion chamber and the altitude of barometric pressure of the air entering the combustion chamber.

The casing surrounding the fuel chamber 37 carries an upstanding bracket arm 63 having a guide bearing 64 therein for receiving the shank 65 of the needle valve 39. A floating lever 66 is pivoted at 67 to the outer end of needle valve shank 65, the upper end of this lever being connected at 68 to a bellows 69 having an air intake conduit 70 leading therefrom, with an air intake opening 71 at the end thereof facing in the direction of movement of the dual jet engine through the air, when mounted on an aircraft. The lower end of the lever 66 is connected at 72 between a closed bellows 73 carried by a bracket 74 projecting laterally from the fuel chamber casing 37, and a coil compression spring 75 seated against the upstanding bracket 63. Changes in altitude of the aircraft utilizing the jet engine varies the air pressure on the exterior of the closed bellows device 73, with the result that the spring 75 rocks the floating lever 66 in ratio to the change in bellows pressure, adjusting the position of the needle valve 39 for the relative changes in altitude. Variations in the speed of the craft and air density likewise varies the pres-

sure of the air entering the conduit 70 through the opening 71, and changes the pressure within the bellows 69, adjusting the position of the upper end of the floating lever 66, and the fuel controlling position of the needle valve 39 to accommodate this change in speed and air pressure.

Means may be provided for varying the setting or fuel air ratio adjustment of the needle valve, such as a threaded adjusting screw 76 carried by a bracket extension 77, from the bracket 63, and connected to the upper end of the floating lever 66 by a spring 78.

While our dual jet propulsion engine is designed to start and run by fuel introduced alternately into the combustion chambers 3 and 4, and compressed and fired by a portion of the jet discharge and the shock of the previously fired jet which is conducted into the other jet discharge tube to compress and fire the charge in the combustion chamber, provision is also made for introducing fuel into both combustion chambers simultaneously, so that the jet units may also fire independently of each other.

It is assumed that high speeds, where the ram effect of the air entering the combustion chambers 3 and 4 through the air intake tubes 23 is sufficiently high, the dual jet units may be fired simultaneously or independently of each other.

Referring again to Fig. 6, the fuel chamber 37 is provided with two by-pass conduits 79 and 80, each having a fuel control valve 81, 82 of the rotary plug type therein. These two valves 81, 82 are normally closed, as shown in full lines, and are provided with operating arms 83 and 84 connected to each other by an operating link 85. The arm 84 has an upwardly extending latch lever portion 86, held in the position shown in full lines, against the tension of a compression spring 87, by a latch member 88, pivotally secured at 89 to the fuel chamber, on an ear projecting from the fuel supply pipe 38, leading from the fuel tank 40.

Raising of the latch 88 releases the valve controlling lever arm 86 and the spring 87 rotates the arm against the stop 90, and the two valves 81 and 82 are shifted to open position. When the valves are shifted to this position, fuel from the chamber 37 by-passes the poppet valves 43 and 44 and is conducted through the by-pass passages 79 and 80 and the connected passages 35 and 36 directly to the headers 31, which supply the spray nozzles 29.

The dual jet propulsion units will now function substantially independent of each other, in a manner similar to conventional reaction jet propulsion engines commonly known as the "buzz bomb" type of jet engine. As before indicated, means may be provided for changing the operation of our improved jet engine from the dual, alternate firing type, to a dual jet independently firing type, when the speed of the aircraft carrying the jet engine increases beyond a predetermined rate.

A bellows 91 is secured to the top of the fuel chamber 37, just under the latch member 88, the bellows 91 having an air inlet pipe 92 with its mouth 93 extending forwardly in the air stream in the direction of travel of the aircraft employing the jet engine. This bellows 91 may be of metallic or Sylphon type so that the inherent resiliency of the same yieldably resisting the expansion thereof regulates the amount of air pressure necessary within the bellows to

raise and release the latch member 88, and consequently prevents raising of the latch until the velocity and pressure of the air passing into its mouth 93 reaches a predetermined rate, sufficient to expand the bellows and release the latch.

Fuel within the fuel tank 40 may be pressurized in any desired well-known manner such as by pumps, or by an air supply conduit 94 having its air inlet 95 disposed in the air stream in the direction of travel. A check valve 96 may also be provided in this air admission pipe 40, and an air pressure reservoir 97 for initially pressurizing the fuel in the tank for starting when air pressure at the air intake 95 is very low.

Another type of fuel metering unit that may be utilized is disclosed in Fig. 7 in which the fuel tank is illustrated at 100, having a fuel delivery conduit 101 with a fuel metering needle valve 124 and check valves 103 and 104 therein, connected to two bellows pumps 105 and 106. These pumps discharge through conduits 107 and 108, having check valves 109 and 110 therein, into the fuel spray nozzles 111, located in the combustion chambers 112 and 113, similar to the spray nozzles 29 in the combustion heads 3 and 4 in Fig. 6. A lever 114 is centrally pivoted at 114a on a bracket 115, the lever having its ends connected to depending bifurcated projections 116 and 117 extending from the actuating bellows members 118 and 119 which are secured on the frame 120, preferably between two combustion chambers 112 and 113. The conduits 121 and 122 lead respectively from the bellows members 119 and 118 to the combustion chambers 113 and 112.

Combustion within the chamber 113, for instance, pressurizes the conduit 121, expanding the bellows 119 which compresses the pump bellows 106 containing fuel. Expansion of the bellows 119 rocks the lever 114 counter-clockwise, raising the abutment 116 from its engagement with the fuel pump bellows 105, simultaneously forcing the abutment 117 downwardly to compress the bellows 106, forcing the fuel therein through the conduit 108 and spray nozzles 111, into the combustion chamber 112. When the mixture in the combustion chamber 112 is ignited, pressure from this combustion chamber pressurizes the pipe 122, expanding the bellows 118 which rocks the lever 114 clockwise, permitting the pump bellows 106 to refill as fuel is being forced from the pump bellows 105 into the combustion chamber 113 through the spray nozzles 111. By utilizing the interconnected pressure and shock wave conducting channel between the two reaction tubes, as disclosed at 9 in Fig. 1, it will be observed that an automatic fuel injection means is provided for introducing fuel alternately into the two jet discharge tubes to maintain the introduction of the fuel in one combustion chamber, in timed ratio to the introduction and ignition of fuel in the other combustion chamber.

Fuel-air ratio control means is also provided in this form of the invention, somewhat similar to that disclosed in Fig. 6. A centrally pivoted floating lever 123 is provided, which carries the fuel metering needle valve 124. The lever 123 is connected at one end intermediate a closed bellows 125 and a compression spring 126. Variations in air pressure due to altitude adjusts the bellows 125 connected to the end of the floating lever 123. The opposite end of the lever 123 is connected to a second bellows 127, having a pres-

sure conduit 128 connected thereto with an air intake opening 129 in the end of the conduit, facing in the direction of travel of the aircraft carrying the device. The bellows 127 is biased by a spring 128, tending to stabilize the position of the right-hand end of the floating lever 123 at various positions, depending upon the air pressure entering the intake opening 129. Variations in altitude and barometric pressure adjust the left-hand end of the floating lever 123, and the needle valve 124 is correspondingly adjusted to regulate the fuel supplied to compensate for the air pressure variations. Variations in the speed of the aircraft carrying the dual jet engine varies the ram effect of the air entering the combustion chambers 112 and 113, and the amount of air entering the air intake 129 for the conduit 128 which causes a variation in the pressure within the bellows 127 and a corresponding adjustment of the right-hand end of the floating lever 123 and predetermined adjustments of the needle valve in a definite ratio to the degree of the ram effect just mentioned.

Referring now to the modified form of our dual jet engine as illustrated in Figs. 8 and 9 of the drawings, this unit is somewhat similar to the form disclosed in Figs. 1 and 5, with the exception that means are provided for continuous operation at high speeds.

Similar parts and structure previously disclosed in Fig. 8, and in Figs. 1 to 5, have been given the same reference characters as in Figs. 1 to 5, and will not be described again in detail in this modification. The spherical combustion chambers 3 and 4 in Fig. 8 are surrounded by rearwardly tapering air collecting casings or jackets 130 and 131, necked down and faired into the discharge jet tubes 5 and 6 as indicated at 132 and 133. The jet discharge outlets from the combustion chambers 3 and 4 are somewhat smaller than the forward ends of the jet discharge tubes 5 and 6 where they join the necked down ends of the jackets 130, 131 so as to leave rearwardly extending air passages 134 and 135 between the rearwardly extending exterior combustion outlet portions of the combustion chambers 3 and 4 and the air collection casings 130 and 131. The combustion outlets from the chambers 3 and 4 instead of being connected directly to the reaction tubes 5 and 6, as disclosed in the first form of the invention, are each provided with a relatively smaller discharge opening 136 or 137, leaving an annular air discharge port surrounding the combustion outlet for discharging the air entering the spaces 134 and 135 between the combustion heads and the air collecting jackets 130 and 131 just within the front portions 12 and 13 of the athodyd chambers 10 and 11.

A plurality of static pressure tubes 138 and 139 extend rearwardly, as shown in Fig. 8, having their forward ends disposed in communication at 140 and 141 with the interior of the combustion chambers 3 and 4. The tubes 138 and 139 taper and curve rearwardly with their rear extremities connected to enlarged header members 142 and 143, having air induction ducts 144, 145 projecting into the jet discharge tubes 5 and 6, and facing forwardly substantially in alignment with the annular air discharge openings 132 and 133 from the casings 130, 131 which surround the discharge openings 136, 137 leading from the spherical combustion chambers 3 and 4.

This form of dual jet engine is preferably supplied with fuel in the same manner as that disclosed in the first form as illustrated in Figs. 1 to

6. At lower velocities the pressures from the explosions in the combustion chambers 3 and 4 (Fig. 8) are transformed into dynamic pressure at the jets from the nozzles 136 and 137, when the static pressures in the jet discharge tubes 5 and 6 reach a low value, permitting air from the ducts 134 and 135, leaving the annular discharge ports 132, 133, to enter the discharge tubes 5 and 6. Since the intake nozzles 144 and 145 project into the jet discharge tubes 5 and 6, just to the rear of the annular ducts 133 and 134, they pick up the dynamic pressure of combustion leaving the combustion chambers 3 and 4, through the short discharge nozzles 136 and 137, and the air entering the front of the casings 130 and 131 around the spherical combustion chambers and leaving through the annular discharge ports 134 and 135.

At low velocities, the ram effect at the auxiliary air ports 12 and 13 is not sufficient to force air through the plural tubes 138 and 139 and into the combustion chambers 3 and 4.

As the air velocities increase, the ram effect of the air entering the air intakes 12 and 13 increases until it has a sufficient ram effect to force the air from the funnel-shaped casings 130 and 131 surrounding the combustion chambers 3 and 4, through the annular air discharge nozzles 132 and 133 into the ducts 144 and 145, and through the curved tubes 138, 139 back into the combustion chambers 3 and 4. When velocities of this magnitude occur, the air pressure and ram effect at the intake nozzle 93 of the air intake tubes 92 (best seen in Fig. 6 and mounted in the free air passing the device and facing the direction of travel) expands the latch release bellows 91, lifting the latch 88 to permit the by-pass valves 81 and 82 to move to their by-passing positions, by-passing the alternately operable fuel admission valve mechanism, so that fuel is fed directly and continuously to the spray nozzles 29 from the pressurized fuel tank 40. Fuel is now fed continuously into the two combustion chambers 3 and 4 (Fig. 8), and air is also fed into the combustion chambers continuously, at these high velocities, by the ram effect of the air entering the intake ducts 144 and 145. This operation results in a continuous operation of both of the combustion units, resulting in a continuous thrust from the propulsion engine.

Briefly summarizing the operation of the preferred form of our invention, as shown in Figs. 1 to 6, before starting the engine, both combustion chambers 3 and 4 should be primed so as to contain a combustible mixture of fuel and air. The switch is then closed to the jump spark plug in the combustion chamber 3, firing the mixture in that chamber. As the explosion occurs, the jet leaving the chamber and a portion thereof entering the jet discharge tube 5 at high supersonic velocity creates a high pressure shock wave and a portion of this shock wave and the pressure gases enters the curved communicating passage 9, and are conducted by the passage 9 toward the discharge opening of the other combustion chamber 4. These hot gases and the high velocity shock wave striking the combustible mixture in the combustion chamber 4 and the forward end of the discharge tube compress the mixture to a degree where it is ignited from the pressure imposed. Even though the combustion chamber 4 should contain no fuel mixture, the pressure in the combustion chamber 3, which has just fired, also enters the conduit 56 leading to the fuel

control unit 28, (as seen in Fig. 6) expanding the bellows 54 to rock the lever 48 counterclockwise and raise the valve push rod 46 to open the poppet valve 44. The opening of the valve 44 admits fuel from the fuel delivery chamber 37, through the conduit 36 and headers 31 to the spray nozzles 29, where the fuel is sprayed under pressure into the combustion chamber 4 just in advance of the arrival of the pressure or shock wave traveling from the combustion chamber 3 through the conduit 9 toward the combustion chamber 4.

As combustion in the chamber 4 takes place, the velocity and inertia of the gases leaving the jet discharge tube 5 create a reduction in pressure in the chamber 4, causing air to be drawn into this chamber through the air inlet tubes 23, past the yieldable spring valves or reeds 25, 26. This reaction in the jet discharge tube 5 occurs as inertia of the discharging gases is overcome when the explosion in the other combustion chamber occurs, pressurizing the bellows 55 through the pipe 57, to open the valve 43 and admit fuel under pressure, to pressurize the fuel line to the spray nozzles 29 in the combustion head 3. When the shock wave from the tube 6 passes along through the conduit 9 and strikes the gases in the combustion chamber 3, these gases are compressed and ignited.

From the foregoing, it will be observed that the dual jet propulsion units will fire alternately, giving a substantially continuous thrust to the engine, also by utilizing the shock wave from the combustion in each unit to assist in the compression of the combustible mixture in the other unit, this, together with the well-known reaction effect of the jet discharge will increase the efficiency of each jet unit and the power output from the engine.

The efficiency of the units is also increased by the employment of the athodyd cooling chambers 10 and 11, since the air that is packed into the enlarged portions 14 and 15 by the ram effect at the entrance 12 and 13 is heated at the enlarged portion, expanded and then permitted to discharge freely toward the rear at high velocity along the exterior of the jet discharge tubes to escape through the thermal air jet discharge openings 19 and 20.

When a sufficient relative velocity of the air passing the jet engine has been obtained, the latch 88 is raised by the air pressure entering the inlet opening 93 (Fig. 6), permitting fuel to be fed directly from the fuel tank to the spray nozzles 29. Under these conditions, both jet units may operate independently of each other as jet propulsion motors. The rate of fuel flow is also regulated by the needle valve 39 to maintain a desired fuel-air ratio for variations in the ram air pressure due to the velocity of the air entering the pipe 71, and by reason of changes in air pressure, due to variations in the altitude, incident to the air pressure effective on the bellows 73.

65 We claim

1. In a dual jet propulsion engine of the class described, a pair of jet propulsion units of the intermittent reaction type, each having a combustion chamber formed with forwardly extending air admission valves and a rearwardly extending jet reaction discharge tube with a jet discharge opening facing rearwardly, means for supplying fuel to said combustion chambers alternately or continuously, air pressure operated control means movable relatively in oppo-

site directions for causing said fuel supply means to operate alternately or continuously and air supply means having an air inlet extending forwardly and connected to the air pressure operated control means for moving the same in one of its directions.

2. In a dual jet propulsion engine of the class described, a pair of spaced parallel jet propulsion units of the intermittent reaction type, each having an enlarged combustion chamber at its forward end with one way air admission valve means therein facing forwardly for admitting air into the combustion chamber when the air pressure immediately ahead of the combustion chamber exceeds a predetermined relative pressure within the combustion chamber, a jet discharge pipe extending rearwardly from the rear end of the combustion chamber and open to atmosphere at its rear end, and in communication at its forward end with the rear end of the combustion chamber, the discharge pipes of the two units extending rearwardly from the combustion chambers in spaced parallel relation to each other, a curved intercommunicating pipe of substantially similar cross sectional area as the forward ends of the discharge pipes, disposed in unrestricted communication with both of the jet discharge pipes at their forward end portions, immediately rearwardly of the combustion chambers, its opposite ends curving forwardly toward the interior of the combustion chambers, and adjustable fuel supply means connected between the said units, adjustable in one position to admit fuel alternately into the combustion chambers and adjustable to a second position to admit fuel continuously into both of said combustion chambers.

3. A jet propulsion engine comprising a pair of spaced side-by-side combustion chambers and jet reaction tubes leading rearwardly therefrom in parallel relation to each other each with a jet discharge opening facing rearwardly, an unrestricted communicating conduit between said jet reaction tubes having its opposite ends extending forwardly in communication with the forward portions of the jet reaction tubes for receiving cyclic impulses of pressure from either combustion chamber and conveying said impulses into the other reaction tube in a direction toward the combustion chamber communicating therewith, means for introducing air into said combustion chamber, and single fuel supply means connected to both of said combustion chambers, selectively operable means for introducing fuel alternately or simultaneously from said single fuel supply means into said combustion chambers.

4. A jet propulsion engine comprising a pair of spaced side-by-side combustion chambers and jet reaction tubes leading rearwardly therefrom in parallel relation to other with jet discharge openings facing rearwardly, an unrestricted communicating conduit between said jet reaction tubes having its opposite ends extending forwardly in communication with the forward portions of the jet reaction tubes for receiving cyclic impulses of pressure from either combustion chamber and conveying said impulses into the other reaction tube in a direction toward the combustion chamber communicating therewith, fuel supply means for supplying fuel alternating or continuously to said combustion chambers, air pressure operated means for interrupting the operation of said alternately operable fuel supply means and supplying fuel di-

rect to both combustion chambers and air pressure supplying means connected to said air pressure operated means having an air pressure supply opening facing forwardly for receiving air therein in proportion to the air passing said jet propulsion engine.

5. A jet propulsion engine comprising spaced parallel jet reaction propulsion units, each having an enlarged combustion chamber with air admission valve means in the forward end thereof for admitting air into the combustion chamber incident to combustion and discharge of the gases therefrom through said jet reaction tubes, fuel introducing means for each combustion chamber comprising pressure operated fuel delivery means connected to the fuel introducing means for each combustion chamber having pressure operated actuator means connected to the other combustion chamber for actuating the fuel delivery means for one combustion chamber by pressure received from combustion within the other combustion chamber to alternately supply fuel to each combustion chamber, means for supplying fuel from said fuel reservoir directly and simultaneously to both of said combustion chambers for simultaneously introducing fuel into both of said combustion chambers, spring closed valve means controlling said last mentioned fuel supplying means, and air operated means for opening said last mentioned valve means having an air inlet port facing forwardly.

6. In a dual jet propulsion engine, a pair of jet propulsion units disposed in spaced parallel side-by-side relation, each unit comprising a combustion chamber extending forwardly with a short jet discharge tube extending rearwardly therefrom, a curved communicating conduit connecting said combustion chambers, a funnel-shaped air collecting jacket surrounding each combustion chamber and with its inlet end facing forwardly and its discharge end extending rearwardly and disposed in communication with the short jet discharge tube for that combustion chamber and terminating in a rearwardly extending elongated jet reaction discharge pipe, a plurality of air collection tubes surrounding each of said jet discharge pipes, having their longitudinal axes disposed in planes passing through the axes of said jet discharge pipes and tubes, with their forward ends disposed in communication with said combustion chambers and their rear ends formed with air collection headers extending into said jet discharge pipes at points rearwardly of said combustion chambers and adjacent the discharge ends of said funnel-shaped air collection jackets, said headers being formed with inlet openings disposed rearwardly of said combustion chamber and jacket discharge ends to receive the air from said funnel-shaped jacket and a portion of the dynamic discharge from said combustion chamber and convey the same forwardly into said combustion chamber, valved air supplying means in the forward portion of each combustion chamber facing forwardly, for supplying air thereto, adjustable fuel supply means connected to both of the combustion chambers for selectively supplying fuel alternately to said combustion chambers, valved fuel supply means for supplying fuel simultaneously to both of said combustion chambers and air pressure operated means movable in one direction for initiating the operation of said last named valve means to supply fuel into both of said combustion chambers simultaneously and continuously and air pressure operated

means having an air inlet port facing forwardly for moving said valved fuel supply means to supply said fuel to both of said combustion chambers simultaneously.

7. In a dual jet propulsion engine, a pair of side-by-side jet propulsion units disposed in spaced parallel relation, each unit including an enlarged, substantially spherical combustion head having a combustion chamber therein formed with a short jet discharge nozzle in its rear face, and air and fuel introducing means in its front face, air collecting funnel means facing forwardly and surrounding each combustion head, terminating in a jet discharge tube extending rearwardly therefrom constructed and arranged to receive air entering said air collection funnel from around said combustion head and to receive a portion of the jet discharge from said combustion chamber through the short jet discharge nozzle in the combustion head, a U-shaped conduit extending between said combustion chambers in communication with said combustion chambers, a plurality of conduits extending forwardly and rearwardly in spaced parallel relation to each other around each of said jet discharge tubes with their forward ends disposed in communication with the interior of said combustion chambers and their rear ends projecting into the interior of said jet discharge tubes and terminating in forwardly facing air collection ports disposed in substantial alignment with the discharge ends of said air collection funnels and the combustion chamber discharge nozzles, to receive air passing into and discharged from said funnel and at least a portion of the gases and the shock waves which are projected from said nozzle incident to combustion within said combustion chambers, and convey the same forwardly into said combustion chambers, means for supplying fuel under pressure to said combustion chambers comprising a fuel supply reservoir, means for delivering fuel therefrom under pressure to said combustion chamber, a valve between said fuel supply means and said fuel introducing means for each combustion chamber for selectively controlling the delivery of fuel thereto, a pressure operated actuator for actuating each of said valves to admit fuel selectively to each of said combustion chambers, said pressure operated actuator having a pressure supply conduit therefor connected to the other combustion chamber for utilizing the combustion pressure within each combustion chamber to introduce fuel into the other combustion chamber, a fuel flow regulating valve in said fuel supply, barometric pressure operated valve adjusting means connected to said fuel flow regulating valve for predetermined adjustments thereof incident to predetermined barometric pressures, and supplemental valve adjusting means comprising an air pressure operating actuating member connected to said fuel flow regulating valve, an air pressure supply conduit therefor having an air inlet opening ex-

tending forwardly to receive air pressure thereto incident to the velocity of air passing said conduit, pressurizing said last named conduit to adjust said regulating valve.

5 8. In a jet propulsion engine of the class described, a plurality of jet propulsion units, each unit comprising a combustion chamber having air admission one-way valve means in one side thereof and a jet discharge port in the opposite side thereof with a jet reaction discharge pipe leading from said discharge port, a curved communication passage extending between said jet reaction pipes having its opposite ends disposed in communication with said jet reaction pipes in directions extending toward said combustion chambers, to alternately receive a portion of the jet discharge from the discharge port of each combustion chamber and jet discharge pipe and convey and discharge the same into the other jet discharge pipe in a direction extending toward its associated combustion chamber, an athodyd casing surrounding each of said combustion chambers and the jet reaction discharge pipe extending therefrom, having a restricted air admission port in its forward end, facing in the same direction as the combustion chamber air introducing valve means, said athodyd having an intermediate enlarged air expansion chamber and a rearwardly converging air discharge passage surrounding said jet reaction discharge pipe, terminating in an air discharge port located adjacent the discharge end of the jet reaction discharge pipe, a pressure operated fuel supply means for supplying fuel to both of said combustion chambers, fuel control valve means intermediate each combustion chamber and the fuel supply means, pressure operated valve actuating means for each valve, a pressure supply conduit therefor disposed in pressure receiving communication with the combustion chamber associated with the valve actuating means for controlling fuel introduced into the other combustion chamber.
